UNITED STATES PATENT OFFICE.

JOHN THOS. McGRATH, OF BLOOMINGTON, ILLINOIS.

GRINDING MACHINE.

Application filed January 15, 1921. Serial No. 427,541.

To all whom it may concern:

Be it known that I, JOHN THOMAS McGRATH, a citizen of the United States, and a resident of Bloomington, in the county of 5 McLean and State of Illinois, have invented certain new and useful Improvements in Grinding Machines; and I do hereby declare that the following is a full, clear, and exact 10 description thereof, reference being had to the accompanying drawings, and to the characters of reference marked thereon, which form a part of this specification.

My invention refers to improvements in grinding machines and, as herein disclosed, 15 has been designed as a universal machine for the purpose of grinding the steam feed pipes and connections for locomotive boilers at the parts thereof where steam tight connections are formed between the various 20 elements of the connections; that is to say, the machine is designed for grinding the seats at the ends of the various pipe and joint elements of such steam connection, including the steam pipe, dry pipe, nigger head, the 25 branches that lead from the nigger head to the steam valve chests, et cetera. While the entire machine has been designed with particular reference to grinding, such steam pipe connections for locomotive boilers, and 30 in its entirety is adapted for properly attending the various connections mentioned, it will be understood that, so far as the broader phases of the invention are concerned, certain mechanical elements of the 35 grinder can be adapted for other grinding purposes, such as the support on which the work is sustained during grinding and the means for giving said support its movement of grinding and lifting.

40 An object of the invention is to provide a grinding machine having very simple mechanism for supporting the element to be ground in suitable coactive relation with a grinding tool or in position to coact with another surface to be ground when the joint surfaces or two pipes or connections are to be ground by moving one surface in grinding relation with its mating surface.

Another object of the invention is to provide 45 in a machine of this character means whereby the two elements to be manipulated, the tool connection and pipe member, or two pipe members, can be maintained in proper axial relation with respect to the bore of the pipe or center of other work to be ground.

Another object of the invention is to provide an improved mechanism for imparting a rocking grinding movement to the tool or other element that is sustained on the support during the grinding operation. 60

A further object of the invention is to provide an improved work holder which is so constructed and is connected with the base of the machine and related to the support for the rocking tool or work as to properly support different shaped pipes, joints, and like connections in the machine while the joint surfaces are being ground thereon. 65

Other objects of the invention are to generally improve and simplify machines of this character, with the end in view of universally adapting the machine to different work and enabling the work to be manipulated and ground by relatively unskilled 70 labor. 75

In the drawings, showing one embodiment of the machine;

Figure 1 is a side elevation of a grinding machine embodying my invention. 80

Figure 2 is a front elevation thereof with parts broken away.

Figure 3 is a section on the line 3—3 of Figure 1.

Figure 4 is a section on the line 4—4 of Figure 2. 85

Figure 5 is a view, partly in side elevation and partly in section, of the lower part of the machine, showing the machine adjusted to grind the central branch of an angle fitting or nigger head constituting one of the elements of a locomotive boiler steam connection. 90

Figure 6 is a horizontal section on the line 6—6 of Figure 5. 95

Figure 7 is a side elevation of the machine, showing it adjusted to grind one of the end seat faces of an angle fitting or nigger head.

Figure 8 is a detail of the tool employed in the adjustment shown in Figure 7, as well 100 also as the adjustment shown in Figures 11 and 12, hereinafter to be described.

Figure 9 is a detail view illustrating the valve for pneumatically lifting the work supporting table and the mechanism for controlling said valve. 105

Figure 10 is a side elevation of the machine, showing it adjusted for grinding the joint between the short stand pipe and the horizontal dry pipe of the locomotive boiler. 110

Figures 11 and 12 illustrate the machine adjusted for grinding the respective opposite

ends of the steam pipes connected to the steam chests.

As shown in said drawings, 15 designates the base of the machine. 16 designates an upright column thereon, shown in Figure 6 as being hollow of oblong cross section. 17 designates an oscillating table which, in some of the adjustments of the machine, supports parts of the work and in 10 other adjustments supports a tool which operates in connection with the work. This table is given a short rocking or rotative oscillatory motion about a vertical axis from a mechanism hereinafter to be described. 15 18 designates a cylinder which contains a piston 19 and the table 17 is supported on the piston through the medium of a piston rod 20 that is attached to the piston and extends upwardly through stuffing box 21 20 in the upper head of the cylinder. There is preferably a loose or ball joint connection, indicated at 22, between the table 17 and the piston rod 20, which permits the part that is supported on said table to 25 align itself relatively to the part with which it coacts, as will hereinafter appear, to produce a true ground joint. This ball joint connection can be produced by providing a ball at the upper end of the rod 20 to enter a socket in an extension 23 on the lower 30 side of the table, and said extension and an adjacent top part of the rod 20 can be relied upon to prevent the table tipping when in its loading position, and which is 35 its lower position, as shown in Figures 1 and 5.

Assuming that the work to be ground is fixedly supported by a suitable device above the table and in vertical alignment with the 40 table axis, it is to be understood that the work, when so supported, is located with its lower end a distance above the table greater than the length of a tool and its adapter, or the length of a pipe or a pipe and its 45 adapter, that are to be severally supported on the table to partake of the oscillatory movement of the table to grind the joint on the supported pipe. This is to enable the grinding tool and its adapter or a pipe 50 connection to be fitted upon and locked to the table, to have ample head room beneath the overhead supported work. Thereafter the table and parts supported thereon are lifted by pressure applied under the piston 19, in a manner hereinafter described, to bring the tool and work to be ground or the two surfaces of the work to be 55 ground into proper grinding relation to each other.

60 After the table and work or tool supported thereon has been lifted to its operative grinding position with respect to the fixed work support on the machine, in the manner to be hereinafter described, rotary

oscillatory movement is imparted to the table by means made as follows:

Said table is provided at one end with an extension or arm 25, (Figures 1, 2, 6 and 7) having a vertical opening provided with interior point bearings for a vertically swingable rod 26, which extends therethrough. Said rod is swiveled at its lower end to a suitable bearing 27 fastened to the base, the swiveling connection embracing a head 28 on the lower end of the rod and suitable spherical socket in the bearing 27. The rod 26 is also provided at its upper end with a like ball or spherical bearing 30, which is adapted to fit within a spherical socket 31 carried by the outer end of a link 32. The other, or inner end, of the link 32 is connected by a crank pin 33 with a crank disc 34 that is rotatably mounted on a stud 35 fixed in any suitable way to the supporting column. The said disc 34 is peripherally geared to mesh with a pinion 36 which, as shown, is fastened on the armature shaft of a motor 37 that is supported on a bracket 38 fixed to one side of the column 16.

With the construction described, it will be observed that rotation of the discs 34 operates, through the link 32, the swinging rod 26 and the table extension 25, to give a movement of oscillation to the table on its central axis, which, in this instance, comprises the bearing ball 22. The crank disc 34 and the connections of the link 32 to the swinging rod 26, relative to the connection of the latter with the table, are such as to give relatively short arcs of oscillatory movement to the table and the work carried thereby.

Preferably the means which deliver a lifting fluid under the piston 19 to lift the table and the parts supported thereon to operative grinding position can be operatively connected to the means which give oscillatory movement to the table, so that thereby the period of contact of the grinding surfaces can be determined with respect to the number of oscillations of the table derived from the mechanism described. A suitable timing mechanism for the grinding operation, which serves to admit fluid pressure under the piston to raise the table and parts supported thereby at the proper time and to release said pressure to permit the table and the parts supported thereon to descend to the lower or loading position of the table, is herein shown and is made as follows:

40 designates a link which is loosely connected at its outer end at 41 to the swinging rod 26 between the plane of the table, when in its loading position, and the upper bearing end 30 of the rod. Said link is loosely connected at its other end to a swinging pawl carrying frame or lever 42 that is piv-

oted on shaft 43, which latter is mounted in an upstanding arm 44 on a valve casing or box 45, as best shown in Figures 1, 3, and 5. Hinged to the frame 42 is a pawl 46, the tooth of which engages a ratchet wheel 47 that is fixed to said shaft 43, so as to cause the shaft to rotate therewith as the ratchet wheel is stepped forward by the pawl.

48 (Figure 9) designates a cam disc also fixed on the shaft 43. Said cam disc is disposed in the plane of the vertical axis of the valve casing 45. It is peripherally concentric to its axis of rotation throughout the principal portion of its circumference and is provided with a relatively short drop or depression 50 which cooperates with the stem of and operates a valve within the casing 45 to admit fluid under pressure at the proper time under the lifting piston 19, and now to be described.

The valve casing is divided into upper and lower chambers 52, 53. The upper chamber is an exhaust chamber, and the lower chamber is adapted to be connected, below a valve therein, by a valved pipe 55 to a source of fluid under pressure, not shown. 54 designates a valved pipe which connects the upper or exhaust chamber 52 with the table raising cylinder 18 below the piston 19 thereof. 56 designates a diaphragm which separates the chambers 52 and 53 and is provided with a communicating port 57. Said port is normally closed by a valve 58, shown as having the form of a disc valve and normally held by a suitable spring against the lower face of the diaphragm 56 to close the port 57. Said casing is also provided with an exhaust port or passage 52' which connects the exhaust chamber 52 of the valve casing to the atmosphere.

Said disc valve 58 is formed on or fixed to a stem 59 that is guided at its lower end in a socket 60 formed in the lower wall of the lower valve chamber, and is guided at its upper end in a socketed enlarged portion 61 of an extension stem 62, which extends through the upper wall of the valve casing for contact with the periphery of the cam 48, before described. A rather strong initially tensioned spring 64 surrounds the valve stem 59 between the end wall of the lower chamber and the valve disc 58 to normally hold the valve in position to close the port 57. The upper end of the valve stem 59 bears against a lighter compression spring 65 which is interposed between it and the end wall of the socket formed in the enlarged portion 61 of the lower end of the extension stem 62, said enlarged portion constituting a piston element that operates in a suitable cylinder 61' to control the exhaust port 52'.

In the operation of the lifting mechanism described, when cooperating with the means for giving oscillatory movement to the table,

the shaft 43, carrying the cam 48, is stepped forward an angular distance equal to the angular dimension of a ratchet tooth. When the cam disc 48 has been stepped forward to bring its raised portion 48' into contact with the valve extension stem 62, said raised portion of the cam first acts to force said extension downwardly against the action of the spring 65. This movement initially closes the upper or exhaust chamber outlet port 52' before pressure is exerted to overcome the spring 64. Thereafter, in the further descent of the valve rod extension, the spring 65 is fully compressed so that endwise movement is given to the valve stem 59 to move the valve 58 off its seat and to establish flow for fluid under pressure from the lower or pressure chamber, through the valve port 57 and pipe 54 beneath the lifting piston 19 in the cylinder 18, to lift the table 17, and the parts supported thereon. The said table will be held in its lifted position during the time the cam projection 48' of the ratchet actuated cam disc is engaged with the valve extension 62, inasmuch as at this time the port 52' is closed by the member 61 and the full fluid pressure of the source is exerted under the lifting piston 19. The peripheral length of the raised portion 48' of the cam 48 is such as to give a sufficient period of time for effecting the grinding operation on the work. After the cam 48' has passed off or away from the valve stem extension 62, the stronger spring 64, assisted by air pressure from chamber 53, raises the valve disc 58 to its seat and closes all the connection between the pressure source and the bottom of the cylinder 18. At this time, by reason of the expansion of the spring 65, the enlargement of the valve rod extension 62 has been forced upwardly to uncover the exhaust passage 52' to permit air to escape from the bottom of said cylinder 18 and to allow the lifting piston to descend.

The peripheral length of the cam disc depression 50 can be determined by the character of the work being operated on, so as to insure proper intervals of grinding bearing between the lifts and descensions of the table, and also to insure between said lifts and descensions proper time to adjust new work in a machine or to apply grinding compound, such as emery and oil and to allow the grinding compound to properly adjust itself on the work face or faces being ground.

The construction so far described constitutes the operative elements to lift the table 17 and parts supported thereon and to oscillate them during grinding operation. In addition to this mechanism, the machine embraces means for supporting and fixedly holding the work in position over and upon the table while being ground. The construction described has been designed to produce

what may be termed a universal machine, in that the work holding means that hold the work upon and above the table are constructed to support work that varies considerably in the shape and dimensions thereof.

The work holding means embrace, in part, suspension means that rise above the column 16 to suspend some of the shapes being ground, in combination with means supported rigidly on said column to hold the suspended work in fixed position. For some kinds of work the suspension means need not be employed, the fixed supporting means at the standard being sufficient.

Referring now more particularly to the detail of the entire supporting means, the same can be made as follows:

67 designates a swinging or rotary crane mounted in a socket 68 of the column 16. It has at its top a horizontal jib 69 braced therefrom by a brace 70. 71 designates a trolley which travels on said jib and from the trolley is suspended a block and tackle 72 for raising and lowering and for supporting a sling clamp 73. A cable 74, trained about the pulleys of the block and tackle, is adapted to be attached at 75 to the crane member to hold the sling clamp and the work engaged therein at a desired height. 77 designates a work holding plate which is hinged to a stud 78 that extends transversely through the top of the column 16. Said plate is provided at the front end of the machine with a flange or head 79 that terminates in a socket piece 80 normal to the plane of the flange. Said socket piece 80 is adapted to receive different forms of holders for different kinds of work, as shown in Figures 1, 2, 3, 4, 11, and 12.

One holder embraces a two part clamp 82 that is provided with a stem 83 which enters the socket 80 and may be fixed therein in any suitable manner, as by a pin 84 that extends through transverse registering openings of the parts. The members of the two part clamp 82 are hinged at one side of the clamp and provided at the other side thereof with lugs 85 to receive a clamping bolt 86. 87 are centering screws which are threaded radially through the clamp members for impingement against the work, as the pipe A shown in Figures 1, 2, and 4. The work A shown in the last mentioned figures is the long horizontal dry steam pipe of a locomotive boiler that is located in the top of the boiler between the stand pipe in the steam dome and the nigger head D at the front of the boiler that connects said dry steam pipe A with the steam chests of the engine.

The same form of tackle or clamp arrangement can also be used with the branch pipes C leading from the nigger head D to the steam chests and for grinding the joints

at both ends thereof, as indicated in Figures 11 and 12. So also the same tackle and clamp arrangement may be used for grinding the joint between the lateral branch a of the dry steam pipe A and the steam pipe E, as shown in Figure 10, in which arrangement it will be observed that the swinging or rotative crane has been swung to carry the jib in the opposite direction from that shown in Figure 1, so that the sling clamp 73 supports one end of the pipe A, while the other end thereof is supported in the clamp 82. The swinging crane 67 is offset at 67' to admit of this last adjustment, as indicated in Figures 3, 10 and 12.

In order that the supporting plate 77 of the column 16 may cooperate with the swinging or suspending support in the manner shown in the figures referred to, said supporting plate 77 is adapted to be turned about its hinge 78 to present the clamp 82 at the proper angles to receive the work, as indicated in Figures 1, 10, 11, and 12. This can be effected by providing the swinging plate 77 with gear teeth to mesh with a pinion 90 that is fixed to a shaft 91 which is rotatably mounted in the column 16 and is provided with a crank arm 92.

The said plate 77 can be angularly adjusted by turning the shaft 91 and can be held in any adjusted position by a locking pin 93 which is adapted to pass through registering openings in the walls of the hollow column 16 and to severally engage suitable openings 94 in the plate 77 which are severally adapted to register with the pin in different positions of adjustment of the plate, as will be clear from an inspection of Figures 1, 10, 11, and 12.

In an adjustment for grinding the joints at the ends of the body of the nigger head D, as shown in Figure 7, an adapter fitting 95 takes the place of the clamp fitting 82, before referred to, and is provided with a flange 96, to which the flange of the central branch d of the nigger head can be bolted to hold it in position for the grinding operation.

In Figures 1, 2, and 3, the nigger head D is adjusted to grind the seat at one end of the branch d. This grinding is effected between said seat and a seat on the adjacent or forward end of the main dry steam pipe, which, in the adjustment shown in Figures 1 and 2, is supported by the fixed and sling clamps 82 and 73, respectively. The nigger head D in this adjustment is supported on the table or support 17 between angle brackets 98, 98, fixed to the table, and a clamp bolt 99 which extends through the upstanding members of the angle brackets 125 and the main body of the nigger head. In the adjustment of the parts shown in Figures 1, 2, 5, and 6, the joints between the normal forward end of the pipe and the nigger head D are ground by pressing the 130

joint faces together, which occurs when the nigger head is lifted by the lifting mechanism described and thereafter oscillating the table 17 and the nigger head carried thereby.

Such grinding of a joint between parts which normally fit together, as a connection in the locomotive boiler, occurs also when grinding the joint between the lower end 10 of the branch *a* of the dry steam pipe A and the lower end of the short stand pipe E, as shown in Figure 10, in grinding adjustment. This short stand pipe in the locomotive boiler is a connection between the 15 dry steam pipe and the throttle valve box in the steam dome of the boiler. The said stand pipe is shown in Figure 10 as supported on the table 17 through the medium of any suitable adapter piece 100, which 20 can be fixed in any suitable manner to the table and can be flanged and bolted to the flanged end of the stand pipe.

In Figure 7 the joints at the ends of the main body of the nigger head are ground 25 by a grinding tool designated as a whole by 101, wherein 102 designates a grinding ring of proper cross section and is supported on the upper end of a post 103. Said post can be fixed at its lower end in any suitable 30 manner to the table, as by means of a flanged member 104 that may be bolted to the table. In the arrangement shown in Figure 7, the suspension means, embracing the swinging crane jib and the block and tackle devices, 35 are not necessary. The said grinding ring 102 of the tool 101 is shown as loosely supported on the upper ends of spider arms 105, suitably offset at said upper ends for interlocking engagement with the inner face of 40 the ring, and are hinged at their lower ends to lugs 106 of a nut 107 that is threaded to the upper end of the post 103. Said nut, and, therefore, the grinding ring 102, may 45 be vertically adjusted on the post 103 by means of the threaded adjustment described between the nut 107 and post 103. The spider arms 105 can be thrown outwardly against the inner face of the ring to hold the ring fixedly on the spider arms by means 50 of a collar 108 that is threaded to the post beneath the nut 107 and is provided with an outwardly flaring or bell shaped upper flange 109 to engage the terminals 110 of the arms 105 below their hinge points, as 55 clearly indicated in Figure 8, the arrangement being such that the upper ends of said arms are forced outwardly into holding engagement with the ring when the collar is threaded upwardly relatively to said terminals. The post 103 of the grinding tool 60 may be provided with adapter sections 111, as indicated in Figures 11 and 12, to adapt the tool head, when in grinding position, to the work being operated upon.

65 It will be noted in Figures 11 and 12

that the sling clamp 73 and the clamping ring 82 can grasp and hold the work at relatively different points of the pipes when grinding the two ends thereof, while at the same time presenting the axis of the terminals of the pipes being ground co-axial to the axis of the grinding tool. Thereafter the seat faces will be properly presented to the tool. In the same manner the steam pipe is supported for grinding the joint 75 faces between one end of the pipe and the nigger head, as shown in Figures 1 and 5, and the other branched end of the said pipe and the stand pipe E, as shown in Figure 10.

The foregoing indicates a universal machine for grinding the joints between the several pipes and angle connections of a locomotive boiler in a manner that permits the different parts to be accurately presented to an opposing grinding surface of a 80 tool, pipe, or fitting. Said construction also enables the different parts to be quickly and readily applied to the machine and fixedly locked in place while a joint is being ground. They serve merely as illustrations of the universal adaptation of a machine constructed in accordance with my invention to works of varying shapes and sizes, and from what has been said, it will be readily apparent that joints may be 85 ground on many other different kinds of work, and also other surfaces than joints on different kinds of work can be ground.

It is also to be understood that the structural details shown and described may be 90 somewhat varied within the spirit and scope of the claims hereto appended, and that the invention is not limited to the illustrated details except as to claims wherein the same 95 are specifically set forth and as imposed by the prior art.

I claim as my invention:

1. A grinding machine for the purpose set forth comprising a table capable of horizontal rotative oscillation and adapted to support a grinding element, means to support the work in line with the grinding element, freely tilttable supporting means for said table at the axis of oscillation thereof, means to lift the table to bring the grinding element into operative relation to the work, and means for imparting to and fro oscillatory grinding movement to said table in a horizontal plane.

2. A grinding machine for the purpose set forth comprising a table capable of horizontal rotative oscillation and adapted to support a grinding element, overhead means to support the work in line with the grinding element, means to lift the table to bring the grinding element into operative relation to the work, and freely tilttable supporting means for said table at the axis of oscillation thereof, means for imparting to and fro oscillatory grinding movement to

6
said table in a horizontal plane, said latter means comprising a swinging member operatively connected to said table eccentrically to its oscillating axis, and power means 5 to vibrate said member.

3. A grinding machine for the purpose set forth comprising a table capable of rotative oscillation and adapted to support a grinding element, means to support the work 10 in line with the grinding element, means to shift the table to bring the grinding element into operative relation to the work, and means for imparting to and fro oscillatory grinding movement to said table, said 15 table being supported by means permitting the table to rock about its axis of oscillation to automatically center the grinding element to the work.

4. In a grinding machine for the purpose 20 set forth, a support for a grinding element, a support for the work and means operative from a single source of power for imparting rotary oscillatory movement to said support and for automatically controlling means to 25 lift the support towards an operative grinding position.

5. A grinding machine for the purpose set forth, comprising a table substantially in 20 a fixed plane capable of rotative oscillation and adapted to support a grinding element, means to support work in line with the grinding element, means to lift the table to an operative grinding position, and means for imparting to and fro oscillatory 25 movement to said table, constructed to control the lifting movement of the table.

6. A grinding machine for the purpose set forth comprising a lifting cylinder, a piston 40 therein having a piston stem, a horizontal table supported by the upper end of said stem by means permitting slight tilting movement of the table relatively to said stem, means to admit fluid beneath the piston to lift said table, and means for imparting 45 rotative oscillatory movement to said table and operatively connected to the fluid admission means.

7. A grinding machine for the purpose set forth comprising a cylinder, a piston therein 50 and its piston rod, a table supported on the rod through a swivel connection, means to admit fluid beneath the piston to lift said table, and means for imparting rotative oscillatory movement to said table.

55 8. A grinding machine for the purpose set forth comprising a cylinder, a piston therein, a table carried by the piston, means to admit fluid beneath the piston to lift said table, means for imparting rotative oscillatory 60 movement to said table, and means operatively associated with the mechanism to give oscillatory movement to the table for controlling admission of fluid to the said cylinder.

65 9. A grinding machine for the purpose set

forth comprising, in combination with overhead means for supporting work, and an oscillatory table to support a grinding element in line with the overhead work, of a member having swinging connection at one 70 end to a fixed part and operatively connected to said table, means operatively connected to the other end of said swinging member to give oscillatory motion to said member and therethrough to the table, and means for lifting and lowering said table relatively to an operative grinding position.

10. A grinding machine for the purpose set forth comprising, in combination with an overhead support for work, an oscillatory, raisable and lowerable table to support a grinding element, of a member having swinging connection at one end to a fixed 80 part and connected between its ends to the table eccentrically to the oscillatory axis of the latter, means operatively connected to the other end of said swinging member to give oscillatory motion to said table, means for lifting and lowering said table towards and from an operative grinding 85 position, and means connected to said swinging member for controlling the lifting and descending movements of said table.

11. A grinding machine for the purpose set forth comprising, in combination with overhead means for supporting work, and a table to support a grinding element in line with the overhead work, of mechanism to impart oscillatory movement to said table, means for lifting and lowering said table 95 relatively to an operative grinding position, said lifting means embracing a cylinder, a piston therein connected to said table, valved means to control the flow of fluid into the cylinder beneath said piston, and means associated with the mechanism for giving oscillatory movement to the support for controlling said valve means.

12. A grinding machine for the purpose set forth comprising, in combination with overhead means to support work, and an oscillatory table to support a grinding element in line with the overhead work, of means to impart oscillatory movement to said table, a cylinder, a piston therein to support said table, fluid pressure means for lifting the support and provided with a controlling valve, a pawl and ratchet mechanism for controlling said valve, and means to operatively connect said pawl and ratchet mechanism to the means to oscillate the table.

13. A grinding machine for the purpose set forth comprising means to support overhead work, a supporting table beneath the work position, mechanism for imparting rotative oscillatory movement to the table, and means for raising the table towards operative grinding position, permitting it to descend to a lower position, embracing a 125 130

- cylinder having a rod to support said table at its upper end, a controlling valve connected to the cylinder below the piston, said valve having an actuating stem, a rotative 65
 5 cam adapted to actuate such stem, and pawl and ratchet mechanism associated with said cam, with means to operatively connect said mechanism to the means which gives rotary oscillatory movement to said table.
- 10 14. A grinding machine for the purpose set forth comprising a base, a fixed column thereon, a cylinder supported on the base, a piston in the cylinder having a rod extending upwardly therefrom, a work table supported by a ball joint on said rod, and a 70
 15 rotative crank disc mounted on the column and operatively connected to the table to give it rotary oscillatory movement, and means to control the rise and descent of said 75
 20 piston.
- 15 15. A grinding machine for the purpose set forth comprising a base, a fixed column thereon, a cylinder supported on the base, a piston in the cylinder having a rod extending upwardly therefrom, a work table supported by a ball joint on said rod, a rotative 80
 25 crank disc mounted on the column and operatively connected to the table to give it rotary oscillatory movement, fluid pressure means to control the rise and descent of said piston, valve mechanism for controlling passage of fluid under pressure to the cylinder beneath the piston, and means operated by the mechanism for oscillating said table to control said valve mechanism.
- 20 16. In a grinding machine for the purpose set forth, a support for a grinding element, means operative from a single source of power for imparting rotary oscillatory movement to said support and for controlling means to lift the support towards an operative grinding position, and an upper work holder above said support pivotally mounted by means to permit the work holder to assume varying angles to the plane of said support, with means to lock the holder in adjusted positions.
- 25 17. In a grinding machine for the purpose set forth, a support for a grinding element, means for imparting rotary oscillatory movement to said support, means to lift said support towards an operative grinding position, a work holder above said table comprising a clamp to engage the work, a swinging gear element rockingly supported on a fixed part, and a rotative pinion meshing with said gear element.
- 30 18. In a grinding machine for the purpose set forth, a support for a grinding element, with means to impart grinding movement thereto, and means to raise said support to operative grinding position, a work holder above said table comprising a clamp 85
 35 to engage the work, a swinging gear element to which said clamp is fixed, and a rotative pinion meshing with said gear element.
- 40 19. In a grinding machine for the purpose set forth, a support for a grinding element with means to impart grinding movement thereto, and means to raise said support to operative grinding position, a work holder above said table comprising a clamp to engage the work, a swinging gear element to 90
 45 which said clamp is fixed, a rotative pinion meshing with said gear element, and an overhead crane and jib carrying a sling clamp to sustain a portion of the overhead work so supported by said clamp.
- 50 20. A grinding machine for the purpose set forth comprising a column, a work clamp having means to angularly and adjustably support it on said column, a work table below the work clamp, and means for imparting rotary oscillatory movement to the table, combined with means for lifting the table towards its operative grinding position.
- 55 21. A grinding machine comprising a column, an adjustable work holder at the upper end of the column having means to vary its angle to the vertical, a grinding table below said work support embracing a raisable and lowerable plate, means to control the raising and lowering of the plate, and means to impart oscillatory movement to said plate comprising a vertically oscillatory member hinged at its lower end to a fixed part and loosely connected between its ends to a part of the table eccentric to the axis of oscillation of the table, a rotative member mounted on said column and a link connected eccentrically to said rotative member and having a hinge connection with the upper end of said vertically oscillatory member.
- 60 22. A grinding machine comprising a column, an adjustable work holder at the upper end of the column having means to vary its angle to the vertical, a grinding table below said work support embracing a raisable and lowerable plate, means to control the raising and lowering of the plate, and means to impart oscillatory movement to said plate comprising a vertically oscillatory member hinged at its lower end to a fixed part and loosely connected between its ends to a part of the table eccentric to the axis of oscillation of the table, a rotative member mounted on said column and means connecting said latter member to the plate raising and lowering control to actuate the latter.
- 65 In witness whereof I claim the foregoing as my invention, I hereunto append my signature this 21st day of December, 1920.
